UNITED STATES PATENT OFFICE.

NOEL RAY STILES, OF LONDON, ENGLAND.

MUSIC ROLL FOR AUTOMATIC MUSIC-PLAYING INSTRUMENTS.

Application filed September 1, 1921. Serial No. 497,673.

To all whom it may concern:

Be it known that NOEL RAY STILES, a citizen of the United States of America, residing at London, England, has invented certain new and useful Improvements in or Connected with Music Rolls for Automatic Music-Playing Instruments, of which the following is a specification.

In spools for music rolls for automatic musical playing instruments the flanged ends or buttons have been made of wood or metal and round, and in such construction should a spool be dropped it will invariably roll away from the person or from the position it is placed in and further such a spool with its wrapped perforated sheet is usually placed in oblong boxes, square in cross section and it is necessary to form a cover to the box to keep the spool and sheet free from dust and if placed in an open ended tubular box dust and dirt can get in at the corners which by reason of both flanged ends being round are left open and further no means are provided for ensuring that the roll shall always occupy a position in the box whereby any marking on the end of the roll can be readily discernible.

Now the object of my invention is to obviate these disadvantages by constructing the two flanged ends or buttons of a spool with the contour of their edges dissimilar and either of the same or dissimilar sizes.

My invention will be clearly understood from the following description aided by the annexed drawings which show two examples of carrying my invention into effect.

Figure 1 is a perspective elevation of a music roll and showing one end or button square.

Figure 2 is a perspective elevation of a box containing a music roll as shown in Figure 1.

Figure 3 is a perspective elevation of a box containing a roll of music, one button of the spool being round and having projections for fitting the opening and correspondingly shaped recesses in the end of the box, the other button also being round but not having projections so that it will pass through the opening in the box.

As an example I may employ an oblong box 1 square in cross section and having one end open and I construct one flanged end 2 of the spool round, and the other end 3 square and insert the roll into the box 1 with the round end 2 first so that when the roll 4 is pushed fully into the box 1 the square end 3 will fill the mouth 5 of the box 1 and close same thus protecting the roll 4 from dust and dirt, the roll 4 being properly positioned for any indication such as is shown on its end to be readily discerned.

The box 1 may be of any shape and one of the flanged ends 3 will correspond and should the opening of the box be circular as at Figure 3 one of the flanged ends of the roll may be provided with stubs 6, 6 engaging niches 7, 7 in the wall of the circular opening.

By this invention the flanged ends or buttons of a spool are provided with outlines or circumferences dissimilar in contour at the edges, that is one end may be circular and the other square, or both ends may be circular one end having a projecting point or points adapted to cooperate with corresponding recesses or depressions in the corresponding end of the container, whereby the legend on the end of the roll may be held in a predetermined position relative to the walls of the container or box.

What I do claim as my invention and desire to secure by Letters Patent is:—

A music roll holder comprising a spool and a container therefor having an opening in one end and recesses communicating with the opening, and projections on the spool corresponding with and adapted to fit in the said recesses.

In testimony whereof I have hereunto set my hand in presence of two subscribing witnesses:

NOEL RAY STILES.

Witnesses:

RICHARD CORE-GARDNER,
HAROLD CORE-GARDNER.
